(No Model.)

O. G. MOORE & M. H. MARCUS.

FIRE ESCAPE.

No. 291,756.

Patented Jan. 8, 1884.

UNITED STATES PATENT OFFICE.

OTIS G. MOORE AND MORRIS H. MARCUS, OF EDENBURG, PENNSYLVANIA.

FIRE-ESCAPE.

SPECIFICATION forming part of Letters Patent No. 291,756, dated January 8, 1884.

Application filed March 22, 1883. (No model.)

To all whom it may concern:

Be it known that we, OTIS G. MOORE and MORRIS H. MARCUS, of Edensburg, in the county of Clarion and State of Pennsylvania, 5 have invented a new and Improved Fire-Escape, of which the following is a full, clear, and exact description.

This invention relates to that class of fire-escapes in which a chute of flexible material 10 extends from a window to the ground, down which chute the persons fleeing from the fire slide.

Reference is to be had to the accompanying drawings, forming part of this specification, 15 in which similar letters of reference indicate corresponding parts in all the figures.

Figure 1 is a perspective view of our improved fire-escape, showing the manner in which it is arranged when in use. Fig. 2 is 20 a perspective view of the same, showing it folded. Fig. 3 is a longitudinal view of the chute.

The tube or chute A, made of flexible material—strong canvas, duck, or sail-cloth being preferred—is made of sections a, sewed or riveted to each other or woven in one piece, which sections are alternately inclined in opposite directions, so that the chute will have a zigzag shape. In order to produce this zigzag shape of the chute, the longitudinal axis 30 of each section must be at an angle to the ends, and not perpendicular to the same. A series of ropes, B, preferably four, are secured to the chute throughout the entire length of the same, and the ends of the ropes above the upper end of the chute are secured to a strong ring, C. A rope, D, preferably covered with cloth or overspun, is also attached to the ring C, and passes loosely down through the chute. 35 The lower end of the chute is slotted longitudinally, to facilitate egress from the same. A ring or hoop, E, is attached to the upper end 40 of the chute for the purpose of holding it open.

When not in use the chute, is folded and is 45 held together by the rope D, passed through it, and is suspended by means of the ring C from a hook, F, fastened to the inner surface of the wall below the window.

If the fire-escape is to be used, it is thrown 50 out of the window, the upper parts of the ropes b resting on the window-sill, and the upper end of the chute being suspended from the hook F. The persons that wish to descend enter the upper end of the chute and slide 55 down the same. They check their descent by grasping the rope D, which is covered, so as not to pain the hands. As the chute is zig-zag-shaped, it prevents a too rapid descent of the persons, even if the chute is held very 60 steep. This is of great importance, as the smooth chutes cannot be used in narrow streets, as they cannot be held at a great inclination to the ground, and the persons would slide through them with such rapidity that 65 they would be maimed and injured by being dashed to the ground. Our improved fire-escape avoids these defects. It is very light, can be folded very compactly, and is 70 inexpensive. The chute is to be about twenty (20) inches in diameter, and can be made any desired length, as circumstances may require. It can be unfolded and thrown out of the window by a child.

Having thus described our invention, we 75 claim as new and desire to secure by Letters Patent—

A fire-escape chute made of a series of tubular sections attached to each other in such a manner as to be inclined to each other alternately in opposite directions, substantially as herein shown and described, and for the purpose set forth.

OTIS G. MOORE.
MORRIS H. MARCUS.
